UNITED STATES PATENT OFFICE.

RALPH E. LEE, OF NEW ORLEANS, LOUISIANA, ASSIGNOR TO THE E. V. BENJAMIN COMPANY, INC., TRADING AS MAGINNIS COTTON MILLS, OF NEW ORLEANS, LOUISIANA, A CORPORATION OF LOUISIANA.

OVERALL GARMENT.

Application filed April 5, 1928. Serial No. 267,650.

The invention relates to new and useful improvements in garments, and more particularly to the pocket construction of an overall garment.

5 An object of the invention is to provide a construction of pocket for an overall garment which is very strong and well supported, and wherein the edges of the body portion of the garment at the pocket opening and also the 10 edges of the pocket are inturned and concealed in the seam joining the pocket to the garment.

In the drawings, Figure 1 is a front view of a portion of an overall garment having the 15 improvement embodied therein.

Fig. 2 is a sectional view, more or less diagrammatic, on the line 2—2 of Fig. 1.

The invention is directed to a pocket construction for an overall garment, and more 20 particularly to the construction of the side pockets of the garment. The body portion of the garment is provided with a pocket opening at each side thereof running diagonally from the waist band to the side seams 25 of the leg portion of the overall. The sections of the garment forming the pocket opening overlap. The pocket includes front and rear sections which are joined to the inner and bottom portions of the pocket.

30 The upper portion of the pocket is secured by the seam at the lower side of the waist band and the side of the pocket at the lower end of the opening is secured by the stitches at the side seam of the overall. The front

35 section of the pocket at the opening extends into an inturned hem fold in the body fabric and is concealed within said hem fold. The rear section of the pocket at the pocket opening has its raw edge inturned and joined to

40 the rear portion of the body of the overall, the edge of which is also inturned, by two parallel lines of stitching. The invention is particularly directed to the construction of the pocket which joins the inner section of

45 the pocket to the body portion along the pocket opening. By inturning the edge portions and stitching through said inturned portions by parallel lines of stitching a very strong and durable support is made for the 50 pocket and the edges of the material are concealed from view both at the pocket entrance and on the inside of the garment.

Referring more in detail to the drawings: The invention is shown as applied to an

overall garment consisting of a body portion 55 1, having a waist band 2. Extending diagonally from the waist band 2 to the side seam 3 of the overall is a pocket opening, which lies along the line $x-x$ of Fig. 1. At the pocket opening the outer section 4 of 60 the body of the overall overlies the inner section 5 of the overall. The pocket is indicated at 6 and includes an inner section 7 and an outer section 8. The pocket material is preferably folded so that the inner section is 65 joined to the outer section of the pocket from the point a to the point b by a folding of the material, thus forming an integral connection. From the point b to the point c the fabric sections forming the pocket are joined 70 by edge covering stitches, and may also be joined by through and through stitches. From the point a to the point d the pocket is secured to the waist band 2 by the lines of stitching along the bottom portion of the 75 waist band. From the point c to the point e the pocket is secured to the side seam by the lines of stitching forming the same.

The outer section 8 of the pocket extends into a hem fold 9 in the outer section 4 of the 80 overall, and is secured therein by parallel lines of stitching 10, 10. This makes a very nice finish for the pocket and, not only conceals the edge of the pocket section, but the hemmed portion of the fabric sections to 85 which the pocket section is stitched, extends up to and is stitched to the waist band, and, therefore, this makes a very durable support for the outer section of the fabric. The inner section 5 of the overall has its edge portion 90 along the pocket opening infolded at 12.

These two fabric portions are joined by lines of stitching 13, 13 which are parallel and which pass through the infolded portions of the fabric sections, thus firmly securing the 95 two sections together. The inturning of the pocket section and the inturning of the fabric section and stitching through the same form rib structures which extend all along the pocket opening and into the waist band seam 100 at the upper end and into the side seam at the lower end. By this construction the raw edges of the material forming the garment and the pocket section are concealed, and a very strong support for the pocket is provided.

It is well known that mechanics often place heavy tools and the like which they are using

in the side pockets of the overall garment, which subjects the pocket to heavy strains. By my improved construction, however, the pocket is so well supported that the support 5 does not give away to this excessive loading of the pocket.

It will be understood, of course, that minor changes in the details of construction and arrangement of the parts may be made without departing from the spirit of the invention 10 as set forth in the appended claim.

Having fully described my invention, what I claim as new and desire to secure by Letters Patent, is:

15 An overall garment comprising a body portion having side pocket openings extending diagonally from the waist band of the overall to the side seam of the same, a pocket including inner and outer sections joined

along their inner edges, said outer section extending into and secured by a hem fold in the outer fabric section at the pocket opening and said inner section of said pocket having its edge inturned and placed against the inner face of the inner fabric section at the 20 pocket opening, said edge of the inner fabric section being inturned and secured to the pocket section by parallel lines of stitching passing through the inturned edge portion of the overall and the inturned edge portion 25 of the pocket, said hem fold in the outer fabric section and said inturned edge of the inner fabric section extending into and secured by the waist band seam at their upper ends and into and secured by the side seam 30 at their lower ends.

In testimony whereof, I affix my signature.
